PATENTED MAR. 24, 1908.

H. D. JAMES.

CONTROLLING SYSTEM FOR ELECTRIC MOTORS.

APPLICATION FILED APR. 3, 1905.

UNITED STATES PATENT OFFICE.

HENRY D. JAMES, OF PITTSBURG, PENNSYLVANIA, ASSIGNOR TO WESTINGHOUSE ELECTRIC & MANUFACTURING COMPANY, A CORPORATION OF PENNSYLVANIA.

CONTROLLING SYSTEM FOR ELECTRIC MOTORS.

No. 882,639.

Specification of Letters Patent. Patented March 24, 1908.

Application filed April 3, 1905. Serial No. 253,632.

To all whom it may concern:

Be it known that I, HENRY D. JAMES, a citizen of the United States, and a resident of Pittsburgh, in the county of Allegheny and State of Pennsylvania, have invented a new and useful Improvement in Controlling Systems for Electric Motors, of which the following is a specification.

My invention relates to systems of control for electric motors, and particularly to such systems as embody reversing switches and means for automatically effecting acceleration of the motors.

The object of my invention is to provide means for preventing the reversing switch from being moved from either of its closed-circuit positions to its "off" position while the counter electromotive force generated by the motor exceeds a predetermined amount.

A further object of my invention is to provide an improved means for causing sections of the motor regulating resistance to be cut out successively and in a predetermined order as the counter electromotive force of the motor rises.

The single figure of the accompanying drawing illustrates a system of control embodying my invention.

The system of control comprises, as its constituent elements, a motor 1 having shunt and series field magnet windings 2 and 3, respectively, a regulating resistance 4, switches 5 for cutting sections of the resistance 4 into and out of circuit, operating magnet windings 6 for the switches 5, interlocking switches 7 that are operated by the main switches 5, a resistance 8, and a switch 9 for cutting the resistance 8 into and out of circuit, a reversing switch 10, operating magnet windings 11 and 12 therefor, circuit-breakers 13 and 14, and a master switch 15.

Mounted upon the armature shaft 16, is a brake-wheel 17, with which a strap 18 is normally drawn into engagement by means of a spring 19. The brake may be released by means of an electro-magnet 20, proper circuit connections of the winding of the electro-magnet being made when circuit-breakers 13 and 14 are closed.

When circuit-breaker 13 is open, the armature 21 of the motor 1 is connected in a closed circuit with a resistance 22. A comparatively high resistance 23 is connected in parallel with the shunt field magnet winding 2 of the motor 1, through which the in-

ductive electromotive force of the field magnet winding is discharged when its circuit is opened. The series field magnet winding 3 is connected in series with more or less of the regulating resistance 4 and is subdivided, its middle or an intermediate point being connected to adjacent terminals 23^a of two of the switches 5.

The stationary contact terminals of the switches 5 are connected to points in the regulating resistance 4, the stationary contact terminal 24 of the first switch 25 of the series being also connected to one stationary contact terminal 26 of the circuit-breaker 14. The outer terminals of the operating magnet windings 6 of the switches 5 are connected to points in the regulating resistance 4 and the inner terminal of each winding is connected to one of the stationary contact terminals of the preceding interlocking switch 7. The other stationary contact terminals of the interlocking switches are connected to one terminal of resistance 8, and contact finger 27 of the reversing switch 10 is connected to the other terminal of said resistance.

The first switch 25 of the series is provided with a dashpot 28, which retards closure thereof and causes section 29 of the regulating resistance 4 to remain in circuit during a period of time that may be predetermined according to the desired conditions of operation.

Operating magnet winding 30 of the switch 9 is connected directly across the supply circuit and is adapted to open the switch 9 when the voltage of the supply circuit exceeds a predetermined amount.

The reversing switch is normally maintained in open-circuit position by means of springs 31 and 32 and is adapted to be retained in its closed-circuit positions by means of retaining magnet windings 33 and 34, the terminals of which are connected to contact fingers on the reversing switch 10 in such a manner that they are connected directly between the terminals of the armature winding 21 when the reversing switch occupies one of its closed-circuit positions.

The retaining magnet windings are energized sufficiently to retain the reversing switch 10 in its corresponding closed-circuit positions when the counter electromotive force generated by the motor exceeds a predetermined amount, and, consequently, the reversing switch 10 may not return to its

open-circuit position and then be moved to the opposite closed-circuit position while the motor is running at a sufficiently high speed in the opposite direction to generate an 5 electromotive force greater than the aforesaid predetermined amount.

The circuit-breakers 13 and 14 are operated by means of electro-magnet windings 35 and 36 and a master switch 15 is provided 10 with a switch arm 37 and suitable contact strips that are so constructed and arranged as to govern the circuits of the operating magnet windings 11 and 12 of the reversing switch 10, magnet windings 35 and 36 of the 15 circuit-breakers 13 and 14, and operating magnet windings 6 of the switches 5.

When the master switch arm 37 is moved into engagement with conducting segment 38, a circuit is established from the positive 20 terminal 39 of the system, through operating magnet winding 11 of the reversing switch 10, conducting segment 38 and switch-arm 37, to the negative terminal 40 of the system, thereby energizing the operating magnet winding 25 11, which throws the reversing switch 10 so that its contact fingers engage the conducting segments on the broken lines F.

If the switch-arm 37 is moved still farther and is brought into engagement with conducting segment 41, a circuit is established 30 from the positive terminal 39 of the system, through operating magnet winding 36 of the circuit-breaker 14 and through operating magnet winding 35 of the circuit-breaker 13, 35 contact finger 27 of the reversing switch 10, conducting segments 42 and 43, contact finger 44, conducting segment 41, switch-arm 37, to the negative terminal 40 of the system. Energizing of the operating magnet windings 40 35 and 36 closes the circuit-breakers 13 and 14 and energy is supplied, through the regulating resistance 4 and the reversing switch 10, to the motor 1 and the brake magnet winding 20 is energized, thereby releasing the 45 brake.

The operating magnet winding 6 is also energized, and the switch 25 and the corresponding interlocking switch 45 are slowly closed, rapid closure being prevented by the 50 dashpot 28. The delay in closure of the switch 25 permits the motor 1 to start and increase in speed and gradually increase the counter electromotive force.

When the switches 25 and 45 have closed, 55 a circuit is established through operating magnet winding 46 of the main switch 47, but sufficient current will not be supplied thereto to operate the switch until the counter electromotive force of the motor has 60 risen to a predetermined value; that is, until the drop in electromotive force over the section 48 has fallen below a predetermined amount.

When the electromotive force of the motor 65 rises to a sufficient predetermined value, the

switch 47 and the corresponding interlocking switch 49 will close, thereby shunting section 48 of the resistance and establishing a circuit through operating magnet winding 50 of the switch 51, closure of which is not effected 70 until the current traversing the section 52 of the regulating resistance 4 has fallen below a predetermined amount.

The successive operation of the switches 5 continues, as just described, until all the 75 regulating resistance 4 has been shunted or cut out of circuit.

When switch 53 has been closed and section 54 of the regulating resistance cut out of circuit, a circuit is established through operating magnet winding 55, and when the drop in electromotive force over section 56 of the series field magnet winding 3 falls below a predetermined amount, switch 57 is closed 80 and cuts out of circuit section 56 of the series 85 field magnet winding 3. In like manner, section 58 of the regulating resistance 4 is shunted, by means of switch 59, when the drop of electromotive force over the section 60 falls below a predetermined amount. 90

It is seen that the sections of the regulating resistance 4 are cut out of circuit successively as the drop in resistance over the sections falls below a predetermined amount, or as the counter electromotive force generated 95 by the motor increases, and the order of closure of the switches which shunt the sections of the resistances is governed by the interlocking switches 7. The voltages at which the operating magnet windings of the main 100 switches become sufficiently energized to operate their corresponding switches may be made approximately the same, or unlike, as desired.

One of the inherent difficulties in systems 105 in which the sections of the regulating resistances are automatically cut out of circuit as the electromotive force of the motor rises, lies in the fact that if the supply voltage increases, the voltage applied to the operating 110 magnet windings for the switches which cut out the sections of the resistance also rises and the intervals between the closure of the switches shorten. The result is that at just the time when it is desired to have the intervals between the closures of the successive 115 switches prolonged until the speed of the motor may increase, the intervals are shortened. The switch 9 is provided for the purpose of introducing resistance 8 into the circuits of the operating magnet windings 6 to retard closure of the switches when the electromotive force of the supply circuit rises above a predetermined amount. 120

I claim as my invention:

1. The combination with a translating device, and a reversing switch that normally occupies an open circuit position, of means for preventing the reversing switch from being moved from one position to another 125 130

while the electromotive force generated by the translating device is greater than a predetermined amount.

2. The combination with a translating device, a reversing switch that normally occupies an open circuit position, and means for operating the reversing switch, of means for preventing the reversing switch from being moved from one position to another while the counter electromotive force generated by the translating device is greater than a predetermined amount.

3. The combination with a translating device and a reversing switch which is normally maintained in its open circuit position, of means for retaining the reversing switch in its closed circuit position while the counter electromotive force generated by the translating device exceeds a predetermined amount.

4. The combination with a translating device, a master switch, a reversing switch which is normally maintained in its open circuit position and electro-magnetic operating means therefor, of electro-magnetic means for retaining the reversing switch in its closed circuit positions while the counter electromotive force generated by the translating device exceeds a predetermined amount.

5. The combination with an electric motor, a reversing switch which is normally maintained in its open circuit position and operating magnet windings therefor, of holding magnet windings that retain the reversing switch in its closed circuit position while the counter electromotive force generated by the motor exceeds a predetermined amount.

6. The combination with an electric motor, a reversing switch which is normally maintained in open circuit position and operating magnet windings therefor, of holding magnet windings the terminals of which are connected to the motor armature terminals and that retain the reversing switch in its closed circuit positions while the counter electromotive force generated by the motor exceeds a predetermined amount.

7. The combination with an electric motor, a reversing switch which is normally maintained in open circuit position and operating magnet windings therefor, of holding magnet windings the terminals of which are connected to the motor armature terminals by the reversing switch and that retain the reversing switch in its closed circuit positions while the electromotive force generated by the motor exceeds a predetermined amount.

8. The combination with a translating device, a resistance, and a plurality of switches for cutting out sections of the resistance, of operating magnet windings for said switches

each having a terminal connected to points in the resistance, interlocking switches operated by the aforesaid switches which control the circuits of the operating magnet windings, a resistance in series with the operating magnet windings, and means for cutting said resistance into the circuit of the operating magnet windings when the voltage applied to the translating device exceeds a predetermined value.

9. The combination with a translating device, a resistance, and a plurality of switches for cutting out sections of the resistance, of operating magnet windings for said switches each having a terminal connected to points in the resistance, interlocking switches operated by the aforesaid switches which control the circuits of the operating magnet windings, a resistance in series with the operating magnet windings, and a switch for cutting said resistance into the circuit of the operating magnet windings when the voltage applied to the translating device exceeds a predetermined value.

10. The combination with a translating device, a resistance, and a plurality of switches for cutting out sections of the resistance, of operating magnet windings for said switches each having a terminal connected to points in the resistance, interlocking switches operated by the aforesaid switches which control the circuits of the operating magnet windings, a resistance in series with the operating magnet windings, and a switch for cutting said resistance into the circuit of the operating magnet windings when the voltage applied to the translating device exceeds a predetermined value.

11. The combination with an electric motor having a series field magnet winding, a resistance in circuit therewith, and switches for removing the resistance and a portion of the series field magnet winding from circuit, of operating magnet windings for the switches, terminals of which are connected to the resistance and series field magnet winding at intervals, interlocking switches operated by the aforesaid switches for controlling the circuits of the operating magnet windings, a second resistance, and means for inserting the same in circuit with the magnet windings when the voltage applied to the device exceeds a predetermined value.

In testimony whereof, I have hereunto subscribed my name this 22nd day of March, 1905.
